UNITED STATES PATENT OFFICE.

MORTIMER LEONARD PACKER AND JAMES MARTIN PACKER, OF COLUMBUS, OHIO.

COOKING RANGE.

Application filed October 21, 1925. Serial No. 64,024.

This invention relates to improvements in cooking ranges and is particularly directed to a combined cooking range and kitchen cabinet.

- 5 One object of the invention resides in the provision of a range of the character specified wherein the base of the range is provided with an article storing and receiving cabinet and wherein an arrangement is provided for 10 preventing the heat, radiated from the burner structure of the range, from practically affecting the temperatures normally prevailing in the cabinet section or base of the range.
- 15 Another object of the invention resides in 15 the provision of a combination range consisting of a cabinet section and a superposed range section between which is situated a wall of insulating material for preventing transmission of heat from the range section to the 20 cabinet section, the cabinet section being provided with features of construction by means of which air circulation is maintained throughout the full area thereof, so as to carry off the heat and maintain the contents 25 of the cabinet section free from the deteriorating action of excessive heat, the circulation maintained in the cabinet section being independent of the heat circulation within the range section.
- 30 A further object of the invention rests in providing a horizontally extending compartment or heat insulating chamber between the cabinet and range sections, and in providing within this chamber a sliding table 35 top or shelf, which upon being extended to an operative or active position will permit the range to be used in the capacity of a table in addition to its other previously recited features.
- 40 With these and other objects in view, as will appear as the description proceeds, the invention consists in the novel features of construction, combinations of elements and arrangements of parts hereinafter to be fully 45 described and pointed out in the appended claim.

In the accompanying drawing:

Figure 1 is a vertical sectional view taken through the improved combination kitchen 50 range comprising the present invention,

Figure 2 is a vertical sectional view on the line 2-2 of Figure 1, and

Figure 3 is a horizontal sectional view on the line 3-3 of Figure 1.

55 Referring more particularly to the drawings the numeral 1 designates our improved

combination range in its entirety. Broadly, the range comprises a base or cabinet section 2 and a superposed range section 3.

In this instance the range is formed from 60 sheet metal, suitably reinforced and braced and the cabinet section 2 consists of a bottom wall 4, a rear wall 5, vertically extending side walls 6 and a front wall 7, suitable supporting legs 8 being provided at the corners of the 65 cabinet section to support the latter above the floor surface 9 upon which the range is positioned. The front wall 7 is provided with an opening closed by a door 10, which provides access to the large compartment 11 70 provided in the cabinet section. Also arranged within the cabinet section to one side thereof, is a frame 12, in which is supported 75 slideable drawers 13, which are capable of being drawn outwardly through openings 75 provided in the front wall 7, as will be readily understood. The upper part of the cabinet section is covered by a top wall 14, which is perforated as at 15 to provide a plurality 80 of ventilating openings. Similarly, the bottom wall 4 is perforated as at 16, and it will be seen that air may enter the cabinet section as indicated by the arrows in Figure 2, and may then circulate throughout the full area 85 of the cabinet section, finally finding vent 85 through the openings 15 provided in the top 14, and the vitiated air is then permitted to escape from the range by way of openings 17, provided in the walls 5 and 6 above the plane of the top wall 14. This arrangement, 90 while of economical design, functions practically and efficiently in removing heat from the cabinet section by providing a natural and effective system of air circulation. It will be noted that the vitiated air is withdrawn from the cabinet section of the range 95 in a manner independent of the action of the upper or range section 3 of said range. In this respect the present invention differs materially from the disclosure set forth and 100 claimed in Patent No. 1,521,832 issued January 6, 1925, to Mortimer L. Packer.

The range section 3 consists of a burner mechanism 18 arranged immediately beneath a stove top or grid 19. At one side of the burner mechanism is situated the baking and broiler ovens 20, which are of customary construction. To prevent the heat radiated from the burner mechanism from practically 105 affecting the temperature in the cabinet section the rear, side and front walls 5, 6 and 7 carry an inwardly situated angle iron frame 110

- 21, upon which is situated a wall 22, formed
from a relatively heavy sheet of insulating
material, such as asbestos, mineral wool, cork
or combinations of these materials. It will
5 be observed by reference to Figure 1, that the
wall 22 is disposed immediately beneath the
burners and will effectively prevent the trans-
mission of heat from one section of the range
to another.
- 10 The wall 22 is disposed in vertically spaced
relation from the top wall 14, and by this ar-
rangement there is provided in the range a
heat dissipating chamber 23. This chamber
is open on all sides, a feature obtained by the
15 openings 17 and also by means of the enlarged
rectangular opening 24 provided in the front
wall 7 adjacent the chamber 23. By this con-
struction free and unrestricted air circulation
20 through the chamber 23 is afforded, serving
to effectively carry off and dissipate any rel-
atively high temperatures which may obtain
in the top of the cabinet section by reason of
the continued and extended use of the burner
25 mechanism. Within the chamber 23 there is
mounted a table top or shelf 25. This mem-
ber is slidably supported within the chamber
23 and, as shown, extends across the full
length of the range, although this length may
30 be varied if found desirable. By the inclu-
sion of the shelf 25 it will be seen that when
the latter is extended, as indicated by dotted
lines, the same may be employed as a table

which may be employed for any kitchen pur-
pose. When not in use the shelf or table is
positioned within the chamber as indicated in 35
full lines in Figure 2, so that the same is out
of the way, and will not interfere with the
free use of the range.

By this construction we have combined in
one article of furniture a cooking mechanism,
a cabinet and a table. By this arrangement
a compact grouping is provided which is both
a convenience and a labor saving appliance
40 for those engaged in cooking or kitchen
activities.

45 What is claimed is:

In a combination kitchen range, a cabinet
section, a superposed range section, said range
section being spaced from said cabinet section
50 to provide a heat dissipating chamber between
said sections, passages leading from said cabi-
net section into said chamber, and passages
establishing communication from said cham-
ber to the atmosphere, a table structure slid-
55 ably mounted within said chamber to assume
active and inactive positions, said table being
so formed or placed within said chamber that
air is permitted to circulate through said
chamber.

60 In testimony whereof we affix our signa-
tures.

MORTIMER LEONARD PACKER.
JAMES MARTIN PACKER.
